UNITED STATES PATENT OFFICE.

CHARLES P. PRICE, OF MALDEN, MASSACHUSETTS, ASSIGNOR TO AMERICAN TAR COMPANY, OF MALDEN, MASSACHUSETTS, A CORPORATION OF MASSACHUSETTS.

STILL FOR CRUDE BITUMINOUS MATERIALS.

1,273,091.

Specification of Letters Patent. Patented July 16, 1918.

Application filed December 3, 1912. Serial No. 734,771.

To all whom it may concern:

Be it known that I, CHARLES P. PRICE, a citizen of the United States, residing at Malden, in the county of Middlesex, State 5 of Massachusetts, have invented certain new and useful Improvements in Stills for Crude Bituminous Materials, of which the following is a description, reference being had to the accompanying drawing and to the figures 10 of reference marked thereon.

The invention relates to new and useful improvements in stills for crude bituminous materials such as water gas tar or coal gas tar, or any other mixtures of tar or artificial oils.

In the distillation of coal tar or other crude bituminous materials where the still is heated by heat applied to the outer surface thereof, there is a great waste of heat owing to the bad heat conducting properties of the residual products which prevent the proper diffusion of the heat through the entire contents of the still. Furthermore, the excessive heat required to dehydrate the 25 bituminous material, often results in a decomposition and the loss of valuable products, while the stagnation or want of diffusion of heat gives rise to carbonization of the pitch, and an accumulation of coked 30 matter on the interior surfaces of the still, which are immediately exposed to the heat, thus deadening the same and obstructing the action of the heat. This accumulation of coked matter requires the action of the still 35 to be suspended periodically in order that said coked material may be removed. This is especially true when heavy oils or coal tar is being dehydrated.

An object of the present invention is to 40 provide a still wherein the heat is applied to the mass throughout the interior thereof, by heating coils which coils are preferably so constructed that one or more may be removed at a time for repairing or replacing, 45 without disturbing the other coils.

A further object of the invention is to provide the still with a plurality of jets of air, which jets are passed centrally through the vertical heating coils for the purpose 50 of causing the bituminous material to circulate in and about the coils, which brings about a much more uniform heating of the

material and a driving off of the distillates in a much shorter period of time.

A further object of the invention is to 55 provide a still which is so constructed that the cover therefor may be readily removed without in any way disturbing the devices for collecting the distillates, which cover is also preferably so constructed that the distillates serve to cause a self-sealing of the 60 cover to the body of the still.

A further object of the invention is to provide devices for collecting the distillates which are condensed on the cover, which 65 distillates are carried off by a steam jet to the condensers therefor.

These and other objects will in part be 70 obvious, and will in part be hereinafter more fully disclosed.

In the drawings which show by way of illustration one embodiment of the invention;

Figure 1 is a part sectional view through 75 a still having my improvements applied thereto;

Fig. 2 is a plan view of the same, with the cover removed;

Fig. 3 is an enlarged detail, showing the 80 manner of sealing the cover to the body of the still, and the collecting of the distillates.

In carrying out the invention, I have provided a still which consists of a body portion properly surrounded by asbestos or other insulating material, so as to retain the 85 heat within the still. In this still are placed vertically arranged heating coils, through which steam may be passed for heating the contents of the still. These coils are so connected to the main steam inlet pipes that 90 one or more of the coils may be disconnected for repair, or for the purpose of substituting other coils.

In order to facilitate the circulation of 95 the bituminous material as it is being heated, I have provided an air pipe which extends underneath each coil and is provided with a plurality of jets through which air may be forced centrally through the coils. The still comprises a metal cover which is 100 free from insulating material so that it may be kept cool for the purpose of condensing the distillates driven off from the mass in the still; these distillates flowing down the

inner surface of the cover will collect in a trough which serves not only as a seal for the cover, but as a means for conveying the distillates to the condenser. In order to assist in drawing the distillates from the still, I have provided a jet of steam which is driven through the outlet pipe which leads to the condensers.

Referring more in detail to the drawings, the still consists of a body portion 1 which is made of any suitable metal. Surrounding the body portion is an insulating material 2 which may be of asbestos or any other suitable material and this insulating material serves to retain the heat within the body of the still. Located in the still as herein shown, are three vertically arranged coils 3, 4 and 5. The coil 3 is connected with an intake pipe 6, which leads from a main supply pipe 7 and is controlled by a cut-out valve 8. The discharge from the coil 3 is conveyed through a pipe 9 which is connected with a main outlet pipe 10 and is controlled by a valve 11. The valve 11 Fig. 2 is preferably so constructed that a long handled wrench may be applied thereto for turning the same. The coil 4 is connected with an intake pipe 12 which in turn connects with the main inlet pipe 7, and is controlled by a hand valve 13. The coil 4 is also connected by a pipe 14 in the main outlet pipe, and is controlled by a valve 15. The coil 5 is connected through the pipe 16 to the main pipe 7, and is controlled by a hand valve 17. The coil 5 is also connected through a pipe 18 to the main outlet 10, and is controlled by a valve 19. These coils serve as a heating means for the still. The steam is passed through the inlet pipe 7 and is led through the pipes 6, 12 and 17, to the various coils, after which the steam passes through the pipes 9, 14 and 18, to the outlet pipe 10. These coils, as clearly shown in Fig. 1, are arranged vertically and extend from a point near the bottom of the still to a point well above the center of the mass of the material in the still. The steam passing through the coils will therefore, be carried in and about the interior of the mass being heated, and said mass will be uniformly heated. If at any time one of the coils should break down or become unfit for use, it may be readily disconnected by closing the valves in the inlet and outlet pipes therefor, after which it may be disconnected from these pipes and removed for repairing or replacing.

In order to further aid in the heating of the mass, I have provided an air pipe 20, Fig. 2. This air pipe, at a point outside the still, is connected with three pipes 21, 22 and 23, each of which has a controlling valve therefor. The pipe 21 extends un-

derneath the coil 3 to a point centrally thereof. Radiating from the pipe 21 at the center of the coil, as herein shown, are four arms 24, each of which is perforated so that jets of air may be forced up through the coil throughout a greater portion of the interior area of the coil, and these jets of air will cause the material to circulate through the coil and thus secure a more thorough diffusion of the heat throughout the mass, and a uniform heating of the same. The pipe 22 leads to the coil 4 and is provided with similar radiating arms 24. The pipe 23 leads to the coil 5, and is also provided with radiating arms 24. It will be noted that the controlling valves for the air are located at a point outside of the still where they may be readily accessible. From the above construction, it will be apparent that I have provided a still wherein the mass contained therein may be thoroughly and uniformly, and also quickly, heated to the proper temperature to drive off the distillates desired.

At the upper edge of the body portion 1 of the still, is an angle iron 25 which is secured to the still and is so shaped as to form a trough 26. The still is closed by a cover 27 which is conical in shape, as herein shown, and the lower edge of the conical-shaped cover is formed with a straight vertical flange 28, which is adapted to be set in the trough 26. A framework 29 extends above the still and is provided with a suitable bracket 30 supporting pulley blocks 31 which may be used for raising the cover 27 from the still. The cover is preferably provided with an opening in one side thereof, which may be closed by a door 32 which is hinged at 33 to the cover and is held closed by a latch 34. This door may be so constructed as to practically seal the opening in the cover when closed.

The distillates are carried from the still by a pipe 35 which is disposed concentrically to the center of the still and is connected to a series of short vertical pipes 36, each of which has a funnel 37 at its upper end. The short vertical pipes 36 Fig. 3 are also connected to short horizontal pipes 38, which are secured at a point adjacent to the upper edge of the still by suitable nuts 39. These short horizontal pipes 38 pass through the upper edge of the still and communicate with the trough 26. The pipes 36 and 38 serve as a supporting means for the circular pipe 35. An inclined pipe 40 connects with the circular pipe, and extends to a point centrally of the still and is provided with a receiving funnel 41 at its upper end. An outlet pipe 42 extends from the pipe 35 through the sides of the still, and is connected with a pipe 43 which leads to a series condenser 44. The inclined sec-

tion 43^a connects the pipe 43 with the condenser 44. The steam pipe 45 extends into the pipe 43 and serves as a means for introducing a forced jet of steam through the pipe 43 to assist in drawing off the distillates collected in the pipe. The second coil condenser 46 is connected with the series condenser 44 and said second condenser may be connected with a suitable storage 10 vessel of any desired character.

In the operation of my device, the crude bituminous material is placed in the still and steam passed through the heating coils. In the preferred use of my device, this crude 15 bituminous material is dehydrated for a suitable period, during which time the water contained therein and the lighter distillates are caused to vaporize and are drawn off through the collecting pipe 35. These 20 distillates condense on the cover 27 and running down the inner surface thereof, will fill the trough 26 until it overflows through the pipe 38 into the collecting pipe 35. The distillates therefore form a self-seal for the 25 cover. The distillates will also be collected through the funnels 37 and 41 and will be drawn off through the collecting pipe 35. The jet of steam passing through the pipe 43, will assist in drawing off these distillates, and will be more or less mixed therewith as they pass to the condenser. The distillates will be collected through the funnels 30 37 and 41 by reason of the fact that the steam jet causes more or less of a vacuum in the pipe 43, and this aids in drawing the distillates into the funnels. The air passing up through the heating coils will cause the mass of material to be properly agitated or to circulate so that the heat from the 35 heating coils will be diffused throughout the entire mass and the same will be uniformly heated. I am able by this construction of still, to drive off the distillates without the use of such excessive heat as would cause 40 the carbonization of the pitch, and an accumulation of coked material either on the interior surfaces of the still or about the heating coil. The still may be supplied with a crude bituminous material through an intake pipe 47, and the material may be drawn 45 from the still through an outlet pipe 48.

The still herein shown, is preferably used for the preparation of tar for use on roads, and when so used, the crude bituminous 50 material after being dehydrated for the period stated, is supplied with asphaltum. Anywhere from one to twenty per cent. of asphaltum is used and this may be inserted in the still in block form, through the opening in the cover closed by the door 32.

It is obvious that the still may be used for other purposes, and that minor changes in the details of construction and arrangement of parts may be made, without depart-

ing from the spirit of the invention as set forth in the appended claims.

Having thus described my invention, what I claim as new and desire to secure by Letters Patent, is:—

1. A still including in combination, a body portion, a cover therefor, a vertical coil arranged within said still through which steam may be passed for heating the material, and means for forcing jets of air centrally up through the coil, for causing the material being heated to circulate through the coil. 70

2. A still including in combination a body portion having a trough at its upper edge, a cover having a seat in said trough whereby the distillates collecting in the trough seal the cover, means for heating the material in said still including a vertically arranged coil through which steam may be passed, and devices for forcing a plurality of jets of air upwardly through the coil. 80

3. A still including in combination a body portion having a trough at its upper edge, a cover having a seat in said trough whereby the distillates collecting in the trough seal the cover, a collecting pipe for the distillates, means for connecting said collecting pipe with said trough, a plurality of vertical pipes leading to said collecting pipe, and funnels supported by said vertical pipes. 85

4. A still including in combination a body portion having a trough at its upper edge, a cover having a seat in said trough whereby the distillates collecting in the trough seal the cover, a collecting pipe for the distillates, means for connecting said collecting pipe with said trough, a plurality of vertical pipes leading to said collecting pipe, funnels supported by said vertical pipes, and means for heating said still including a vertically arranged coil located within the still, through which steam may be passed. 100

5. A still including in combination a body portion having a trough at its upper edge, a cover having a seat in said trough whereby the distillates collecting in the trough seal the cover, a collecting pipe for the distillates, means for connecting said collecting pipe with said trough, a plurality of vertical pipes leading to said collecting pipe, funnels supported by said vertical pipes, means for heating said still including a vertically arranged coil located within the still, through which steam may be passed, and devices for causing a plurality of jets of air to pass upwardly through said coil. 115

6. A still including in combination a body portion having a trough at its upper end, a conical-shaped cover having a flange adapted to seat in said trough, a collecting pipe located in said still adjacent the upper edge of the body portion, pipes connecting 120

said collecting pipe with said trough at points above the bottom of the trough, whereby the distillates in the trough will seal the cover, an outlet pipe connected with 5 said collecting pipe, and means for forcing steam into said outlet pipe for drawing the distillates from the collecting pipe.

In testimony whereof, I affix my signature, in the presence of two witnesses.

CHARLES P. PRICE.
